UNITED STATES PATENT OFFICE

CAMILLE DREYFUS, OF NEW YORK, N. Y.

FABRIC CONTAINING ORGANIC DERIVATIVE OF CELLULOSE YARN

No Drawing.

Application filed July 16, 1930. Serial No. 468,480.

This invention relates to fabric containing 5
yarns of organic derivatives of cellulose and
relates more particularly to the preparation
of fabric having yarns of cellulose acetate,
which fabric is of more uniform appearance
than has been heretofore possible.

An object of my invention is to prepare
fabric containing yarns of organic derivatives
of cellulose, which fabric has a uniform
10 appearance. A further object is to
avoid the appearance of streaks and the like
in fabrics by employing more or less opaque
yarn of cellulose acetate as at least part of
the yarn of which the fabric is constructed.
15 Other objects of this invention will appear
from the following detailed description.

Yarns of cellulose acetate or other organic
derivatives of cellulose as ordinarily made
20 are more or less transparent. Moreover the
lustre of such yarn is often not absolutely
uniform. Therefore fabric made of such
yarn often does not have a uniform appearance,
its lustre is not as brilliant as may be
25 desired, and it shows warp streaks due to
the unevenness of the tension of the warp and
to the difference of lustre of the warp yarns,
weft bars where the weft pirns have been
changed, wood grain effects and other
30 streaks. I have found that this is due to
the fact that the yarn is so transparent that
most of the irregularities of the warp and
weft are visible through them. Moreover
pile fabric having pile made of such more or
35 less transparent yarns does not have a uniform
sheen or brilliant lustre or appearance
for the same reasons.

I have found that if yarns of cellulose
acetate or other organic derivatives of cellulose
40 which have their transparency reduced
or their opacity increased are employed in
whole or in part in making the fabric, the
above difficulties are avoided wholly or to
a substantial degree and fabric of substantially
45 uniform appearance and free from bars,
streaks and the like and which has more
covering power may be made.

In accordance with my invention I prepare
a woven fabric containing yarns of cellulose acetate or other organic derivatives
50 of cellulose of increased opacity, whereby

any streaks and the like either do not occur
or are not visible.

While this invention will be described specifically in connection with yarn made of cellulose acetate, it is equally applicable to 55
yarns made of other organic derivatives of cellulose such as cellulose ester and cellulose ethers. Examples of such cellulose esters are cellulose formate, cellulose propionate and cellulose butyrate, while examples of 60 such cellulose ethers are ethyl cellulose, methyl cellulose and benzyl cellulose.

The yarns of cellulose acetate may have their opacity increased or their transparency decreased in any suitable manner. Thus 65
the yarns may have a finely divided pigment such as titanium oxide, barium sulfate, barium phosphate, zinc oxide, zinc sulfide, lead sulfate or lithophone, etc. disseminated throughout the filaments thereof. This may 70 be done by incorporating the finely divided pigments in amounts say of 0.5 to 3% of the weight of the cellulose acetate in the spinning dope from which the yarns are formed. If desired the yarns may have their opacity 75 increased by treating the same with an aqueous solution of a metal salt, either in the presence or absence of a swelling agent for the cellulose acetate, and then the yarn treated with a solution of a substance that 80 causes the precipitation of the insoluble pigment.

Another mode of increasing the opacity is to treat yarn of say acetone soluble cellulose acetate with boiling water or wet steam. 85
It is to be noted that it is immaterial whether the lustre of the yarn is reduced or not provided its opacity is increased.

In carrying out this invention, the fabric may be made wholly of the yarn of increased opacity. However in many cases it is preferable to use such opaque yarn as only one component of the fabric while the other component may be normal yarn of organic derivatives of cellulose of normal 95 transparency or yarns made of other fibres such as natural silk, cotton or reconstituted cellulose. For instance if a cotton warp is employed, the irregularities of this warp are much less apparent when an opaque yarn 100

is used as weft or filling than in the case where transparent yarn is so used.

In pile fabric such as velvets having a back of cotton, natural silk or reconstituted cellulose, by employing the relatively opaque cellulose acetate yarn as pile, any streakiness of the back is hidden by the opacity of the pile yarn so that the fabric is of substantially uniform appearance and of increased lustre and sheen.

In the case of knit fabric and articles such as hose, less distortions and holes are apparent when the opaque cellulose acetate yarns are employed, in accordance with this invention. By way of example it is pointed out that if a fabric is constructed of warp of the ordinary cellulose acetate yarn and a weft of yarn of increased opacity, streaks due to unevenness of the tension of the warp 20 yarns or the difference of lustre between the warp yarns is hidden by the opaqueness of the weft yarn. Moreover no weft bars are apparent at those places where the weft 25 purl has been changed. A further advantage of the fabric made by this invention is that the fabric on the whole is less transparent than fabric made wholly of transparent cellulose acetate yarn, which is important when the fabric is used as lining for 30 coats and the like. Moreover a fabric made by this invention while employing a yarn containing finely divided pigment, wears longer and can be rubbed more times without injury than can the fabric made wholly 35 of the ordinary cellulose acetate yarn.

It is to be understood that the foregoing description is given merely by way of illustration and that many variations may be made therein without departing from the 40 spirit of my invention.

Having described my invention, what I claim and desire to secure by Letters Patent is:

1. Method of preparing a fabric that is 45 substantially free of warp streaks comprising weaving a warp consisting of normal yarns with a weft consisting wholly of yarns of organic derivatives of cellulose of increased opacity.

50 2. Method of preparing a fabric that is substantially free of warp streaks comprising weaving a warp consisting of normal yarns with a weft consisting wholly of yarns of cellulose acetate of increased opacity.

55 3. Method of preparing a fabric that is substantially free of warp streaks comprising weaving a warp consisting of normal yarns with a weft consisting wholly of yarns of cellulose acetate of increased opacity having a finely divided pigment therein.

60 4. A fabric of substantially uniform appearance and free of warp streaks having a weft of organic derivative of cellulose yarn of increased opacity and a warp of yarn of 65 normal lustre.

5. A fabric of substantially uniform appearance and free of warp streaks having a weft of cellulose acetate yarn of increased opacity and a warp of yarn of normal lustre.

70 6. A fabric of substantially uniform appearance and free of warp streaks having a weft of cellulose acetate yarn of increased opacity containing a finely divided pigment therein and a warp of yarn of normal lustre.

75 In testimony whereof, I have hereunto subscribed my name.

CAMILLE DREYFUS.
